UNITED STATES PATENT OFFICE.

EDWIN B. LANE, OF WEST HOBOKEN, NEW JERSEY.

VALVE.

1,415,249.

Specification of Letters Patent. Patented May 9, 1922.

Application filed June 17, 1918. Serial No. 240,837.

To all whom it may concern:

Be it known that I, EDWIN B. LANE, a citizen of the United States, and a resident of West Hoboken, in the county of Hudson and 5 State of New Jersey, have invented an Improvement in Valves, of which the following is a specification.

This invention relates to valves, and with regard to certain more specific features, to a 10 valve controlled by electric current.

Among the several objects of the invention may be noted the provision of a simple and durable valve that is reliable in action, inexpensive to construct, and practically 15 proof against derangement even by severe service conditions; the provision of a valve of the above general type having actuating devices that require a minimum amount of energy without sacrifice of certainty of operation; and the provision of an electrically- 20 operated valve that can be manufactured at low cost and readily installed, and requiring only the momentary application of power to its coils to operate the several parts of the 25 mechanism. Other objects will be in part obvious and in part pointed out hereinafter.

The invention accordingly consists in the features of construction, combinations of elements and arrangement of parts which will 30 be exemplified in the structure hereinafter described and the scope of the application of which will be indicated in the following claims.

In the accompanying drawings in which 35 is shown one of various possible embodiments of this invention,

Figure 1 is a sectional elevation on the line 1—1 of Figure 2, showing a preferred embodiment of his invention.

40 Figure 2 is a plan of the valve of Figure 1, with the cover removed, and showing portions of the device in section.

Figure 3 is an end elevation of the valve viewed in the direction of the arrow 3 in 45 Figure 1.

Figure 4 is a diagrammatic illustration of a preferred system of electrical connections.

Similar reference characters indicate corresponding parts throughout the several 50 views of the drawings.

Referring now more particularly to Fig-

ures 1, 2 and 3 of the accompanying drawings, there is shown at 1 the base or casing of a valve which may be used to control the flow of fluid for any one of a variety of purposes, 55 including the heating of a room or space or receptacle whose temperature is to be kept within predetermined limits. The fluid that is controlled by the valve may be the actual heating fluid or it may be the fuel for the 60 heating device; and the fluid may be liquid or gaseous.

The valve comprises generally a pair of actuating coils, one adapted for opening and the other for closing the valve; the valve 65 body per se; the valve stem; and parts actuated by the energizing of the coils for moving the valve stem in one direction or the other.

The frame 2 serves for a mounting for the 70 coils 4 and 5, the former serving in the present instance to close the valve and the latter to open it. A spacing device 6, preferably non-magnetic, connects the two parts of the coil frame 2 at their lower extremities and 75 is held in position thereon by suitable retaining devices, such as the screws 7. The coils are provided with sleeves or linings 8 and the usual insulation 9 is provided between the sleeves 8 and the windings of the 80 coil.

Above the coils and extending across the housing or casing 1, is a tube 11, preferably 85 non-magnetic, in which is carried a ball 12, which is free to roll back and forth within the tube. For many purposes this ball may be replaced by shot or liquid or other convenient mass whose weight, exerted first at one end of the tube and then at the other, serves to hold the tube in position against 90 accidental derangement. Stops 10 limit the travel of the ball, and preferably seal the tube, to protect the ball from steam, gas, moisture or other deleterious matter.

Mounted at either end of the centrally piv. 95 oted tube or runway 11 is a core 13 slidable within the respective solenoid coil 4, 5, and so related to the coil that energization of the coil causes the core to be pulled downwardly. In Figure 1 of the drawings the parts are 100 shown in the position they occupy after the energization of the closing coil 4. Suitable

nonmagnetic plugs or spacing devices 33 prevent the movable cores 13 from sticking at the lower end of their stroke by reason of residual magnetism. A mass 34 is provided 5 on the same side of the runway 11 as the lever 14, and is of such weight and distance from the pivot 19 of the runway, as to balance the weight of the movable part 15 of the valve, which is exerted upon the under side 10 of the runway at the point of contact of the lever 14 therewith. This makes the runway balanced except for the traveling mass 12, and ensures an equal certainty of operation 15 regardless of the direction in which the mass 12 is traveling.

The closing coil 4 and the opening coil 5 are preferably operated from a source of power such as the battery 36 (Figure 4) through the medium of a thermostat 37, the 20 movable member 38 of which is adapted to contact with the terminal 39 when the valve should be closed, as for example, when the room is too hot, and with the terminal 40 when the valve should be opened, as, for example, 25 when the room is too cold. With the parts in the positions indicated in Figures 1 and 4, the closing of the circuit through the valve-opening contact 40 energizes the valve-opening coil 5 from the battery 36 through the movable part 38 of the thermostat, valve-opening contact 40 of the thermostat, right-hand binding post 28, right-hand vertically-movable cup 27 thereon, and runway 11, as will be clear from Figure 4. This causes the right-hand core 13 to be pulled downwardly. During the first 30 part of the downward movement of the core, the contact at the parts 27-11 is maintained because the cup 27 has a limited range of vertical movement upon its binding post 28, the upper and lower limits of this range being indicated by the relative positions of the right-hand and left-hand cups 27 respectively. When, however, the core 13 has 35 been drawn downwardly far enough to ensure the reversal of inclination of the runway 11, and to insure the traveling of the mass 12 to the right-hand half of the runway, the cup 27 reaches the downward limit of its range of movement, whereupon the further downward travel of the runway 11 breaks the circuit between the cup and the runway and thereby deenergizes the coil 5. Thus the valve is operated with only a 40 momentary application of power to the coil 4 or 5, and the movement of the valve stem 15 automatically opens the coil circuit and thereby minimizes the energy required for the operation of the valve. It will be noted, 45 moreover, that this breaking of the circuit does not occur at the thermostat, so that the thermostat contacts, which are often comparatively delicate, are not subjected to the arcs attendant upon the breaking of the 50 circuits. The binding posts 28 may be in-

sulated from the frame or casing 22 in any suitable way, as by means of the insulating bushings 26.

When the valve is in its closed position, the passage of fluid therethrough may be entirely stopped or only partly stopped. The latter construction is indicated in Figure 1, and is advantageous when it is desired to have a small flow of fluid through the conduit at all times, as, for example, when the 70 fluid is gas passing to a burner, and the gas is to be kept burning without the use of a separate pilot light. In order that the travel of the stem 15 may be adjusted so as to close the valve completely or only partially, the 75 stem is freely mounted in an adjustable seat 42 which is provided with threads engaging the lower part of the valve body 16 and with threads of smaller diameter engaging a flanged or shouldered lock nut 43 which 80 rests against the lower portion of the valve body 16 and is protected from steam, gas, or other deleterious matter by a cap 45, which is illustrated as screw-threaded upon the valve body 16. By backing off the lock 85 nut 43, the adjustable seat 42 may be raised or lowered by turning it in its threads, and may be secured in its adjusted position by tightening against the lock nut. In this manner the lowermost limit of travel of the 90 valve stem 15 may be adjusted as desired.

In view of the above, it will be seen that the several objects of the invention are achieved and other advantageous results attained.

100

As various possible embodiments might be made of the above invention and as various changes might be made in the embodiment above set forth, it is to be understood that all matter herein set forth or shown in the 105 accompanying drawings is to be interpreted as illustrative and not in a limiting sense.

I claim:

1. A valve combining a conduit, a movable part adapted to control the flow of fluid 110 in said conduit, a pair of solenoids adapted respectively to move said part in one direction or the other, cores for said solenoids, a runway centrally pivoted and connected at either end with said cores, the initial movement of either core serving to reverse the inclination of the runway, a mass movable in the runway, whereby said mass travels to the other end of the runway and remains there, to hold said part in its new 115 position, and means outside the runway whereby the circuit of the solenoid is broken during the movement of its core, after said mass has started to travel down the runway.

2. A valve combining a conduit, a movable part adapted to control the passage of fluid through a conduit, a pair of coils, cores therewith, a pivoted runway connected at either end to said cores and connected to said part and normally inclined in one di- 125 130

rection when the valve is open and in the other direction when the valve is closed, the energization of either coil causing its core to be drawn downwardly to reverse the 5 inclination of the runway, a mass in the runway adapted to travel therein upon said reversal, and means outside the runway for

breaking the circuit of the energized coil during movement of its core.

In testimony whereof, I have signed my 10 name to this specification this fifteenth day of June, 1918.

EDWIN B. LANE.
